UNITED STATES PATENT OFFICE

LOUIS R. DAVIDSON, OF NEW YORK, N. Y.

PNEUMOTHORAX APPARATUS

Application filed October 9, 1931. Serial No. 567,809.

This invention relates to a small extremely portable pneumothorax apparatus. My improvements are directed to means, in a device of this character, including a five-way valve, whereby the pressure in the pleural cavity may be measured, whereby a measured quantity of air may be introduced into said cavity, and whereby air may be removed from said cavity, all by the easy and unassisted manipulation of said five-way valve for effecting suitable connections between the inlets and outlets thereof, with a manometer, with a pair of reservoirs, and with the operating needle.

15 The reservoirs are movable vertically in opposite directions and are connected at their lower ends so that the contained liquid will successively expel air therefrom and aspirate air therein, these movements of the 20 reservoirs being controlled in and by the operation of the valve, which operation serves to bring into registry the appropriate valve vents and the passages leading therefrom and thereto.

25 Other features and advantages of my invention will hereinafter appear.

In the drawings:

Figure 1 is an elevation of the combined enclosing case and stand for my improved 30 apparatus.

Fig. 2 is a longitudinal section thereof.

Fig. 3 is a section on the line 3—3 of Fig. 2.

Fig. 4 is a partial horizontal section showing the case employed as a stand for the apparatus, taken on the line 4—4 of Fig. 5.

Fig. 5 is a front elevation of the apparatus.

Fig. 6 is a side elevation.

Fig. 7 is a side sectional view.

Fig. 8 is an enlarged detail view, partly in 40 section of the valve casing and valve.

Fig. 9 is a section on the line 9—9 of Fig. 8, showing the valve turned to one setting thereof.

Figs. 10, 11 and 12 are similar views, respectively showing different valve settings.

Fig. 13 is a view of a modified form of valve, having a further vent, and bores permitting of an additional connection with a mercury manometer.

Fig. 14 is a diagrammatic view of the res-

ervoirs, as moved in opposite directions for the respective operations of liquid and air displacement.

The mount for my improved apparatus is in the form of a panel, having the face portion 1, rearwardly extending side walls 2, 2, and flanges 3, 3. Supported by the face portion 1, near its upper end, is a five-way valve having the casing 4 and revolvable stem 5, which latter is provided with a handle 6, having a pointer 6a, which is adapted to register with gradation marks that are placed around the valve casing in the manner of a dial 6b.

The valve stem extends through the back 65 of the valve casing and is there provided with a sprocket wheel 7, a sprocket chain 8 connecting said wheel 7 with an idle sprocket wheel 9 that is journalled on a stub shaft 10 which is secured to face portion 1 near 70 its lower end.

Frames 11, 11 have lugs 12 that are 75 slideable in slots 13 formed in the walls 2, said lugs engaging the chain 8 respectively at opposite sides thereof, said frames 11, 11, respectively supporting the reservoirs 14, 15, which may be composed of glass, and are provided with suitable calibrations.

Four of the vents in the valve casing 4 are in the same transverse plane, vent 16 being 80 at the top, 17 at the bottom, 18 at the left side and 19 at the right side. A fifth vent, 20, is provided at the bottom, forward of the vent 17. These vents are respectively provided with the rigid tubes 16a, 17a, 18a, 19a 85 and 20a. The valve stem or male element 5 has grooves 21, 22 formed therein which permit the formation of passageways between pairs of vents in the casing, according to the settings of the valve stem to suit the various 90 purposes of the apparatus. Also the valve stem has an angular bore 21a therethrough which in a given valve setting connects the vent 16, by way of groove 21a, with vent 20. At another setting groove 21b connects vent 17 with vent 20.

The vent tube 20a is connected by a rubber tube 23 to a U-shaped water manometer 24, which is here shown as mounted on the face portion 1 of the panel, the limbs of said 100

manometer having a glass stop cock at each upper end.

In practice I have provided this manometer with a working distance of 22 cm., its bore, 5 like the bore in the valve casing is $3\frac{1}{2}$ mm., and the same calibre of bore exists in the glass stop cocks, thus eliminating eddying effects.

The rubber tubing throughout has a working 10 diameter of 4 mm.

The vent tubes 18a and 19a are respectively connected by rubber tubing 25, 26, to the upper ends of the reservoirs 14, 15. These reservoirs each have a capacity of 100 15 cc., and contain a five percent phenol solution. Said reservoirs, which each have a lower opening, are connected thereby with a rubber tube 27, so that liquid may flow from one reservoir to the other, dependent upon 20 the relative positions of the reservoirs.

The lower vent tube 17a is connected by a rubber tube 27a, with a calcium tube 28, which holds sterilized cotton wool, and which is firmly fastened to the panel as by clip 29.

25 In Fig. 5 there is shown a rubber tube 30 as connected with the vent tube 16a, said tube 30 being interrupted by a calcium tube 31, which contains sterilized cotton wool, the tube 30 being adapted to carry the usual 30 form of hollow needle (not shown) for insertion into the pleural cavity.

In brief then the apparatus is constituted by connecting a five-way valve to a manometer and by the use of two vertically and 35 diametrically movable reservoirs whose movements are controlled by a sprocket chain, which chain is operated by turning the valve stem. It is apparent that the respective positions of the reservoirs and the valve are 40 synchronized in the movements of the valve stem handle.

In the employment of the apparatus, when 45 set up, the cut off clamps 32 being released, and the stop cocks 33 being opened by turning them to the vertical position, first the pointer 6a of the valve stem handle is turned to A on the dial, bringing the valve stem to the position shown in Fig. 11, also elevating reservoir 15 and lowering reservoir 14, as 50 shown in Fig. 14. Assuming the dial to be calibrated like a clock face the point A will represent 10:30 o'clock. This permits reservoir 15 to be all but completely emptied. With the liquid in the reservoirs leveled the 55 pointer 6a is turned to 12:00 o'clock, thereby connecting vents 16 and 20 by way of bore 21a, and the pneumothorax needle is inserted in the pleural cavity. Having obtained the proper reading after noting the fluctuations 60 in the right limb of the manometer, the pointer is again turned to A, 10:30 o'clock, and the air contained in the reservoir (75 cc.) is aspirated into the pleural cavity. This is 65 the primary procedure in an initial filling.

When the level of the liquid in reservoir 15

ascends a definite distance, thereby indicating that air has entered the pleural cavity, the fear of embolism is lost. The following procedures are then instituted as for refills.

The pointer is turned to the open position, 70 at 7:30 o'clock, whereby liquid flows from reservoir 15 to reservoir 14, the latter becoming filled with phenoled water and the former charged with filtered atmospheric air. Then the handle 6 is turned to bring the pointer to 12:00 o'clock and if this is a refill 75 the needle is inserted into the pleural cavity through an intercostal space. When the proper reading has been obtained the handle is smartly turned clockwise through 135 degrees, to 4:30 o'clock. Liquid now runs from reservoir 14 to reservoir 15, displacing the air in the latter, which displaced air is thereby 80 forced into the pleural cavity. When all this air (100 cc.) is expelled by the liquid the handle is again smartly turned, this time counter-clockwise, through 270 degrees, to 7:30 85 o'clock.

In the previous position, while the air was leaving the reservoir 15, and the liquid was flowing from reservoir 14 to reservoir 15, air was entering reservoir 14.

It is to be noted that the liquid exchange is exact and constant, and eliminates siphonage, depending only upon the ever present 90 force of gravity. If during the operation pressure readings are desired the pointer is immediately turned to 12:00 o'clock, thereby connecting the manometer with the pleural cavity. After having ascertained the 95 readings the pointer is returned to its previous position and filtered air is again displaced from the respective reservoir, which is calibrated, into the pleural cavity. It is apparent that by continuously turning the handle 100 clockwise and counter-clockwise a limitless amount of air can be introduced. Utilizing 105 this manœuvre a positive pressure of 16 cm. of water can be obtained. However, if greater 110 pressures are wanted, particularly by those who desire to stretch adhesions, the following 115 procedure is adopted:

When the manometer indicates a positive 120 pressure of about 14 cm., a small rubber bulb, such as is customarily used with a nasal atomizer, is slipped over the tube 28. When 125 this bulb is slowly squeezed filtered air exerts pressure upon the surface of liquid in one reservoir, thereby forcing air from the other reservoir into the pleural cavity, and, if considerable air under pressure is necessary, and this I sincerely doubt, and the air in one reservoir is completely emptied, the handle is again reversed through 270 degrees and the pressure bulb is again slowly squeezed. Frequent manometric readings should be taken 130 when creating high pressures.

By removing the distal rubber tubing from filter tube 30, and connecting it to filter tube 28, then performing the procedures as 135

for refills, air is removed from the pleural cavity. However, manometric readings in this instance are not available unless appropriate connections are made by turning the 5 pointer to 9:00 o'clock. For the purpose of withdrawing air from the pleural cavity, the pointer for the valve stem is turned to 7:30 o'clock, as for introducing air into the pleural cavity. The partial vacuum created in reservoir 10 15 will draw air from the pleural cavity. Also upon reversing the positions of the reservoirs the air withdrawal will be effected by the partial vacuum in reservoir 14.

The valve shown in Fig. 13 is like the valve 15 shown in the other figures, excepting that in Fig. 13 there is an additional vent 22c, having a tube 22d. The purpose of the additional vent is for a double reading, where higher pressures are met with, and in this instance 20 vent 22c is in communication with a mercury manometer (not shown), vent 22c connecting with vent 16 through a bore 22a provided for the purpose. When relieving pleural pressures, in order to effect the reading through 25 vent 17, the groove 22b is provided in the stem of the valve shown in Fig. 3, and establishes communication between vent 17 and vent 22c.

For convenience in transporting the apparatus 30 I have provided the box illustrated in Fig. 1, which is provided with grooves for the secure lodgement of the apparatus therein; and also said box, when the apparatus has been removed therefrom, serves the 35 purpose of a stand for supporting the apparatus in a vertical position, for service.

Variations within the spirit and scope of my invention are equally comprehended by the foregoing disclosure.

40 I claim:

1. The combination, in a pneumothorax apparatus, having reservoirs that are vertically movable in opposite directions, and are in communication at their lower portions, of 45 a five-way valve having a casing and a stem revolvable therein, said casing provided with five vents and said stem having passageways that selectively connect certain of said vents, respective means of communication between 50 the upper portions of said reservoirs and said valve, a manometer, means of communication between said valve and manometer under the direct control of said valve, and means actu-

ated by the operation of said valve stem to move said reservoirs oppositely.

2. The combination, in a pneumothorax apparatus, having reservoirs that are vertically movable in opposite directions, and are in communication at their lower portions, of 70 a five-way valve having a casing and a stem revolvable therein, said casing provided with five vents and said stem having passageways that selectively connect certain of said vents, respective means of communication between the upper portions of said reservoirs and said valve, a manometer, respective means of communication between said valve, manometer, and a pneumothorax needle, and means actuated by the operation of said valve stem to move said reservoirs oppositely.

3. The combination, in a pneumothorax apparatus, having reservoirs that are vertically movable in opposite directions, and are 80 in communication at their lower portions, of a valve having a casing and a stem revolvable therein, said casing provided with a plurality of vents and said stem having passageways that selectively connect certain of 85 said vents, respective means of communication between the upper portions of said reservoirs and said valve, a water manometer, respective means of communication between said valve, water manometer and a pneumothorax needle, also between said valve and a mercury manometer, and means actuated by the operation of said valve stem to move said reservoirs oppositely.

4. In a pneumothorax apparatus, reservoirs vertically movable in opposite directions and being interconnected at their lower portions, a manometer, a calcium tube, a pneumothorax needle, a five-way valve including a casing having four vents connected to said reservoirs, said manometer and said needle, respectively, and also having a vent in communication with said calcium tube, a revolvable valve stem having a pair of grooves to permit the formation of passageways between a selected reservoir and the needle and calcium tube, and further presenting an annular bore adapted to connect said needle to said manometer and also having a groove to connect said calcium tube to said manometer, and means actuated by the operation of said valve stem to move said reservoirs oppositely.

LOUIS R. DAVIDSON.
